UNITED STATES PATENT OFFICE.

DANIEL J. CARR, OF COFFEYVILLE, KANSAS.

WRENCH.

1,278,590.

Specification of Letters Patent. Patented Sept. 10, 1918.

Application filed May 29, 1918. Serial No. 237,253.

To all whom it may concern:

Be it known that I, DANIEL J. CARR, a citizen of the United States, residing at Coffeyville, in the county of Montgomery and 5 State of Kansas, have invented new and useful Improvements in Wrenches, of which the following is a specification.

This invention relates to wrenches and it consists in the novel features hereinafter described and claimed.

An object of the invention is to provide a wrench of simple and durable structure the parts of which may be easily and quickly adjusted to fit different sizes of nuts or bolt 15 heads, there being also provided simple means for securely holding the parts at the adjusted position.

Another object is to provide in combination with the wrench proper a detachable 20 jaw member which may be used when the wrench is employed for turning hexagonal or oxagonal parts.

With these objects in view the wrench comprises a bar having a jaw fixed at one 25 end thereof and provided at the jaw with a loop. The said bar is further provided at one edge with a set of teeth. The wrench includes a second bar having teeth adapted to engage the teeth of the first mentioned bar, 30 the second mentioned bar being slidably received in the loop. The second mentioned bar is provided with a fixed jaw adapted to coöperate with the first mentioned jaw in grasping an object. A spring is attached to 35 the second mentioned bar and bears against the edge of the first mentioned bar. A clip is mounted upon the second mentioned bar and is provided with outstanding lugs. The said outstanding lugs are received in L-shaped slots which are provided in a yoke 40 slidably mounted upon the first mentioned bar. A jaw member is provided and may be mounted upon the fixed jaw of the first mentioned bar and the said jaw member is provided with an inclined edge having serrations or teeth and is used when the implement is employed for turning hexagonal or 45 oxagonal objects.

In the accompanying drawing:—

50 Figure 1 is a side view of the wrench showing the parts in one position.

Fig. 2 is a similar view showing the parts in another position and parts broken away.

Fig. 3 is a perspective view of a yoke used 55 on the wrench.

Fig. 4 is a similar view of a detachable jaw which may be applied to the wrench.

Fig. 5 is a fragmentary perspective view of the end portion of one of the bars of the wrench.

The wrench comprises a bar 1 which is provided at one edge with a series of teeth 2. A fixed jaw 3 is carried at one end of the bar 1 and a loop 4 is mounted upon the jaw 3.

The wrench also includes a movable bar 5 having at one edge teeth 6 which may engage the teeth 2. The bar 5 is slidably received in the loop 4. The bar 5 is provided at one end with a fixed jaw 7 which is adapted to coöperate with the jaw 3 when the wrench is used upon objects having rectangularly disposed sides. A clip 8 is mounted upon the bar 5 and is provided at its sides with outstanding lugs 9.

The end portions of the clip 8 lie at the sides of the bar 1. The clip 8 is fixed with relation to the bar 5. A yoke member 10 is slidably mounted upon the bar 1 and is provided at its sides with L-shaped slots 11.

The slots 11 receive the lugs 9. A spring 12 is attached to one end of the bar 5 and bears at its free end against the edge of the bar 1. The spring 12 has a tendency to hold the end of the bars 5 and 1 away from each other and the teeth which disengage from the teeth 2.

When the ends of the bars 1 and 5 are forced toward each other the teeth 2 will engage between the teeth 6 and the lugs 9 may be moved into these angularly disposed end portions of the slots 11 whereby the bars 1 and 5 are fixed with relation to each other.

Therefore the said bars may be moved longitudinally with respect to each other and a nut or bolt head may be received between the opposite faces of the jaws 3 and 7.

When it is desired to use the wrench for turning objects which have their sides arranged in the form of an oxagon or hexagon a jaw member 13 is applied to the jaw 3. The said jaw member 13 is provided with an inclined edge having teeth or serrations 14. Plates 15 are located at the opposite sides of the jaw member 13 and may lie against the sides of the jaw 3. A pivot bolt 16 may be passed transversely through the plates 15 and the jaw 3 whereby the jaw member 13 is held in position upon the jaw 3.

The pivotal connection between the jaw 3 and the jaw member 13 may be sufficiently 110

loose to permit the member 13 to have slight swinging or rocking movement with relation to the jaw 3 when the wrench is in operation. Therefore the jaw 3 may have a 5 swinging movement similar to that found in the type of wrench generally known as a Stilson wrench.

From the foregoing description taken in conjunction with the accompanying drawing, it will be seen that a wrench of simple and durable structure is provided and that the parts thereof may be easily and quickly adjusted and when adjusted may be securely held at the adjusted position.

15 Having described the invention what is claimed is:—

A wrench comprising a bar provided at its edge with teeth and having a fixed jaw, a

loop mounted upon the jaw, a second bar having teeth adapted to engage the first mentioned teeth, the second mentioned bar being slidably received in the loop, the second mentioned bar having a jaw, a spring carried by the second mentioned bar and bearing against the edge of the first mentioned bar and normally holding the two sets of teeth spaced from each other, a clip 20 fixed to the second mentioned bar and having outstanding lugs, and a yoke slidably mounted upon the first mentioned bar and 25 having L-shaped slots which receive the said lugs and which hold the two sets of teeth in engagement with each other when the lugs are in the end portions of the slots.

30 In testimony whereof I affix my signature. 35

DANIEL J. CARR.
